UNITED STATES PATENT OFFICE

2,239,171

SADIRON REST

William E. Gundelfinger, St. Louis, Mo., assignor
to Knapp-Monarch Company, St. Louis, Mo., a
corporation of Missouri

Application September 12, 1938, Serial No. 229,565

4 Claims. (Cl. 38—79)

An object of my present invention is to provide a rest for sadirons particularly adaptable as a means to cooperate with the handle of the sadiron and permit rest or non-ironing position of the sadiron with the sole plate uppermost at a laterally inclined angle and the handle of the rest serving as a three-point support for the sadiron in non-ironing position.

A further object is to provide a sadiron rest comprising a projection such as a rail or the like at the side of the sadiron casing, which projection is so spaced by a support relative to the iron that it is maintained comparatively cool and thereby may be placed in contact with the ironingboard or table without danger of burning it, and the projection being so located with respect to the handle of the sadiron that the projection and handle cooperate with each other to provide a support that is substantial enough to eliminate easy tipping of the iron from its rest position with its center of gravity then falling substantially midway between the handle and rest.

Another object of my invention is to provide a rest particularly adaptable for sadirons of the kind shown in the application of Howard A. Smith, Serial No. 126,455, filed February 18, 1937, wherein is shown a round sadiron, although it is also applicable to sadirons of the usual shape.

The foregoing, other and further objects of the invention will be apparent from the following description, accompanying drawing and appended claims. Embodiments of the invention are illustrated in the accompanying drawing in which the views thereof are as follows:

Figure 1 is a perspective view of a sadiron structure with my rest applied thereto;

Figure 2 is a side elevation of the sadiron when tipped to rest position, the iron being viewed from the side where the operator would normally stand;

Figure 3 is a rear elevation of the iron in the position of Figure 2;

Figure 4 is an enlarged sectional view on the line 4—4 of Figure 1, and

Figure 5 is a plan view on a reduced scale showing my rest applied to an ordinary shape of sadiron.

On the accompanying drawing I have used the reference numeral 19 to indicate a sole plate, and 12 a shell of a sadiron. The sadiron shown in Figures 1, 2 and 3 is circular in plan view and has a handle 13.

Supporting brackets 14 and 15 support the handle 13 relative to the shell 12. The usual terminal prongs 16 are provided for connection with a supply cord plug (not shown) partially enclosed

by a guard 17. The foregoing iron is disclosed in detail in the Howard A. Smith application hereinbefore referred to.

My rest member includes a ring 18 formed of metallic tubing or the like and a plurality of supports 19 for supporting it relative to the shell 12. The manner of support may comprise an arrangement such as shown in Figure 4. Screws 20 extend through perforations 21 in the shell 12 and terminate in threaded openings 22 of the tube 18. The tubes 19 thereby serve as spacers.

The rest 18, being in the form of a ring entirely around the periphery of a shell 12, serves as a guard in many instances to prevent undesirable contact of the cloth being ironed with the shell 12 during the ironing process. Such contact would prematurely dry out the cloth whereas it is desirable to prevent such a contingency particularly where intricate portions of the dress or the like are being ironed and part of the cloth has to be held off the ironingboard while advancing the iron along the cloth. It is therefore evident that the ring shape of the rest 18 serves a useful purpose in addition to the rest serving its primary purpose, as will hereinafter appear.

When the iron is to be left in a non-ironing position, it is merely necessary for the operator to tip it toward himself to the position shown in Figure 2. This position is for a right-hand person, whereas tipping it in the opposite direction would be proper for a left-hand person.

In Figure 3 the iron is viewed from the rear and its angle of inclination as well as the contact of the periphery of the ring 18 with the supporting surface S is clearly illustrated. The ring 18 serves as one point of support while the handle 13 serves as another point of support. Preferably, the handle 13 contacts with the surface S at two points as shown in Figure 2 adjacent the ends of the handle, so that a three-point support is had.

The spacers 19 are preferably located spaced from the point of contact of the rest 18 with the surface S. This point is shown at 18^a in Figures 1 and 2 so that by placing the spacers 19 at forty-five degrees (45°) to the point 18^a, there is a minimum of heat transmission from the shell 12 to the point 18^a. Also due to the spacing of the ring 18 from the shell 12, so that there is room for free air circulation between the ring and the shell, the heat of the shell is effectively dissipated before it reaches the point 18^a and such point is therefore comparatively cool, even though the parts 18 and 19 are formed of metal.

In Figure 5 I show a modified construction in

which arcuate rests 13^b have end portions 13^c secured to a shell 12^a of an ordinary shape of sadiron. The handle is indicated at 13^a and cooperates with the arcuate rest 13^b in the same manner as disclosed in Figure 2.

My rest arrangement enables the operator to merely tip the iron toward himself when desiring to position the iron at rest. This is a very simple operation, and likewise the operation of engaging the handle and tipping the iron to ironing position is very simple. A less awkward wrist motion is thereby involved than when the iron is up-ended rearwardly, as is the usual practice.

My invention has been described in the foregoing specification and illustrated in the drawing, more or less precisely as to details. It is to be understood, however, that changes may be made in the arrangement and proportions of parts and equivalents may be substituted without departing from the spirit and scope of the invention as set forth in the appended claims.

What I claim and desire to secure by Letters Patent of the United States is:

1. In combination with a round sadiron having an elongated handle, a continuous curved rail-like element extending around said sadiron, spaced therefrom and adapted to cooperate with said handle to support said sadiron in inverted and laterally inclined position, resting on said 30

handle and on a portion of said rail-like element, and supports extending from said sadiron to said rail-like element, said supports being connected to said rail-like element at positions along the length thereof substantially spaced from the above-mentioned rest portion thereof.

2. The combination with a circular sadiron having a horizontally elongated handle lying in the plane of one diameter, of a circular rail-like element substantially concentric with the sides of said sadiron and spaced therefrom, and support means extending from said sadiron to said rail-like element at positions along the length thereof substantially spaced from the diameter perpendicular to said first-mentioned diameter.

3. A sadiron having a sole plate of circular outline, a shell covering said sole plate, and an annular guard rail supported on said shell concentrically with said sole plate, spaced above the bottom surface of said sole plate and spaced outwardly from the periphery of said sole plate.

4. In combination with a sadiron having a sole plate of circular outline, a shell covering said sole plate, a horizontally elongated handle extending across said iron and supported above said shell, and a continuous rail-like element extending around said iron, and supported on said shell concentrically with said sole plate.

WILLIAM E. GUNDELFINGER.
